CLAIM

The ornamental design for a box, as shown and described.

DESCRIPTION

FIG. 1 is a top, front, and side perspective view of a box showing our new design, with the closure flap shown in a closed condition; and,

FIG. 2 is a top, front, and side perspective view thereof, with the closure flap shown in an open condition.

The dashed lines shown in FIG. 1 represent tear lines. The sides opposite those shown and the bottom are flat and unornamented.
